UNITED STATES PATENT OFFICE.

GILES B. DOUD, OF WINONA, MINNESOTA.

REFRIGERATOR.

1,248,288.

Specification of Letters Patent. Patented Nov. 27, 1917.

Application filed July 3, 1914. Serial No. 848,929.

To all whom it may concern:

Be it known that I, GILES B. DOUD, a citizen of the United States, resident of Winona, in the county of Winona and State 5 of Minnesota, have made a certain new and useful Invention in Refrigerators; and I declare the following to be a full, clear, and exact description of the same, such as will enable others skilled in the art to 10 which it appertains to make and use the invention, reference being had to the accompanying drawings, and to letters or figures of reference marked thereon, which form a part of this specification.

15 Figure 1 is a vertical section of the refrigerator on the line 1—1 Fig. 2.

Fig. 2 is a horizontal section on the line 2—2 Fig. 1.

Fig. 3 is a detail perspective view of one 20 of the trays.

Fig. 4 is a detail perspective view of one of the strap hinges.

Fig. 5 is a detail perspective view of one of the hinge pintles.

25 Fig. 6 is a detail section on the line 6—6 Fig. 1.

The invention has relation to an improvement in refrigerators, and it consists in the novel construction and combination of 30 parts, as hereinafter set forth.

The object of the invention, primarily, is to provide quadrant-form shelves of maximum capacity, which when swung outwardly through an arc of ninety degrees may be 35 slid upwardly and removed.

In the accompanying drawings the numeral 2 indicates the case, having a chamber provided with a back wall 3 and two side walls 4, 4, which extend vertically upward 40 from the bottom to the top, the front wall of the casing being provided with an opening 5 for a hinged door 6.

In the chamber are swinging trays 8, arranged in series one above another, these 45 trays being of quadrant contour and hinged usually to the jamb of the doorway. The straight radial sides 9 of each tray are nearly as long as the doorway is wide, and are at right angles with each other, being 50 connected by a curved wall 12, which is provided with a number of openings 13 for the passage of air, said openings being preferably comparatively large and arranged in zig-zag relation, in order to provide for 55 better circulation of the air. The bottom of the tray consists of a grating 14, and its

side walls are preferably made integral, of sheet metal. Each tray has a hinge eye 15, usually made of strap metal, the central portion of the strap being bent into eye form 60 and the strap branches being in contact to form a short shank 16 from the eye to their right-angular divergence at a point 17 just inside the angle of the tray wall, these branches from this point extending, 65 one, 18, in the plane of the shank, and the other, 19, at right angles thereto. There are preferably two hinge eyes, one above the other, to each tray. The short shank is of a length equal to the thickness of and extends through a slot 21 in the wall of the tray at one side and immediately adjacent to the angular bend thereof, in bracing engagement with the walls or edges of the slot 21, the straight branch 18 being solidly riveted or connected to the front wall of the tray and the right-angle branch to its lateral wall. These hinge members are therefore 70 strongly fastened to the walls of the tray and, extending along the same in parallel 75 relation, serve to brace the walls and hold them from sagging. The complementary pintle members 22 of the hinges are arranged in vertical series and secured to the inner part of the jamb of the casing doorway, having reduced, laterally offset lower portions from which the pintles extend upwardly. The shank and body of each hinge eye is offset laterally in such manner that the outer sides of both radial walls of each 80 shelf are made substantially tangential thereto, the top of each hinge pindle being spaced apart from the bottom of the lower reduced portion of the hinge member 22 next thereabove by a distance slightly 85 greater than the thickness of a hinge eye 15, so that when the lower tray is swung outward through the doorway it can be 90 cleared from the tray above it, being in this way easily disconnected by lifting it from 95 the pindle or from the casing members of the hinges for removal when required, and when turned back into the chamber of the refrigerator the offset shank 16 and the branch 18 in line therewith are brought inward to position just back of and parallel 100 to the door when closed. As stated, two hinge eyes are usually provided for each tray, these eyes engaging separate slots 21 of the tray and pivoting upon separate 105 hinge pintles, the tray being in this way 110 better supported against sagging. These

trays are designed to facilitate inspection and access to their contents, and as they are independently movable and removable, tend to keep the contents of the refrigerator in orderly arrangement and to provide against unnecessary inflow of warm air through the doorway.

When the trays are removed from the refrigerator chamber, leaving the sheer vertical walls, there is no obstruction to minute inspection of these walls, and thorough cleansing is facilitated.

What I claim is:—

In a refrigerator, a casing having a doorway and a lateral wall provided with a vertical series of hinge members having respectively laterally offset reduced lower portions and hinge pintles projecting upwardly from said reduced portions and spaced apart from each other, a hinged door engaging said doorway, a series of overlying removable quadrant-form shelves located in rear of said doorway, in close relation to each other and having each radial walls,

one of said walls having perforations, hinge straps located upon the inner side of and secured to the radial walls of each shelf, said straps each centrally doubled and having a short shank of a length equal to the thickness of and engaging the perforations of a radial shelf wall, and hinge eyes spaced apart and located immediately adjacent to and in contact with the shelf corners, said shanks and said eyes laterally offset and the outer sides of both radial walls of each shelf tangential to the hinge eyes relating thereto, the top of each hinge pintle being spaced apart from the bottom of the hinge member next thereabove by a distance slightly greater than the thickness of a hinge eye.

In testimony whereof I affix my signature, in presence of two witnesses.

GILES B. DOUD.
